UNITED STATES PATENT OFFICE.

CHARLES L. DREHER, OF LANCASTER, PENNSYLVANIA.

DESIGN FOR A HANDLE FOR CANES, UMBRELLAS, &c.

SPECIFICATION forming part of Design No. 19,846, dated May 20, 1890.

Application filed April 16, 1890. Serial No. 348,236. Term of patent 3½ years.

To all whom it may concern:

Be it known that I, CHARLES L. DREHER, of Lancaster, in the county of Lancaster and State of Pennsylvania, have invented certain 5 new and useful Improvements in Designs for Cane and Umbrella and Parasol Handles; and I do hereby declare the following to be a full, clear, and exact description of the invention, such as will enable others skilled in the 10 art to which it pertains to make and use it, reference being had to the accompanying drawing, which forms part of this specification.

My invention relates to an improvement in 15 designs for cane, umbrella, and parasol handles; and it consists in the conventional representation of a shepherd's crook, around the surface of which are a number of grooves or beads in imitation of a spirally-wound cord or 20 other similar device, as will be more fully described hereinafter.

The accompanying photographic representation shows a side elevation of a handle showing my design.

25 A represents the main portion of the handle, which is shaped somewhat similar to a shepherd's crook, and which has a curved outline and in general contour tapers to the outer end. At the inner end of this handle A are formed the two horizontal beads B, which are 30 separated a suitable distance apart. Formed around this handle A are the inclined beads C, which represent a cord or other similar object, which is wrapped around the curved portion, as shown. The outer and upper end of 35 the hook is curved outward to the point D, as shown, imparting to the handle a continuous curve from one end to the other and giving it a pleasing shape.

Having thus described my invention, I 40 claim—

The design for a cane, umbrella, or parasol handle, substantially as shown and described.

In testimony whereof I affix my signature in presence of two witnesses.

CHAS. L. DREHER.
